HAND MAGNIFIER

Martin Annis, Gilbert Davidson, Armand G. La Selva, and Raymond St. Martin, Cambridge, Mass., assignors to American Science and Engineering, Inc., Cambridge, Mass., a corporation of Massachusetts

Filed Feb. 16, 1968, Ser. No. 10,607

Term of patent 14 years

Int. Cl. D16—08

U.S. Cl. D57—1

FIG. 1

FIG. 2

FIG. 1 is a perspective view of a hand magnifier showing our new design, the undisclosed bottom side being a mirror image of the top; and

FIG. 2 is a side elevational view thereof.

We claim:

The ornamental design for a hand magnifier, as shown and described.
